UNITED STATES PATENT OFFICE.

HUGH CAMPBELL, OF NEWTOWN, CONNECTICUT.

IMPROVEMENT IN LUBRICATORS.

Specification forming part of Letters Patent No. 40,673, dated November 24, 1863.

To all whom it may concern:

Be it known that I, HUGH CAMPBELL, of Newtown, in the county of Fairfield and State of Connecticut, have invented a new and useful Improvement in Grease-Cups; and I do hereby declare that the following is a full, clear, and exact description of the same, reference being had to the accompanying drawing, making a part of this specification, and to the letters of reference marked thereon.

In lubricating the cylinders of steam engines it has hitherto been necessary in low-pressure engines to open the grease-cock when it is on the side of the piston open to the exhaust, so that the pressure of the external atmosphere would force the oil or melted tallow to the inside of the cylinder. In rapidly-working engines—such as are usually attached to screw-propellers—there is too little time to admit the grease in this manner, as the cock must be closed before the steam is admitted to that end of the cylinder for the return-stroke, or else the grease would be blown from the cup and into the engine-room. It is also exceedingly objectionable, that in admitting the grease into the exhaust end of the cylinder a large portion is carried with the exhaust into the condenser without even coming in contact with the internal surface of the cylinder, and is therefore entirely lost. In high-pressure engines, where, even on the exhaust side, the pressure is always greater than that of the atmosphere, it has been necessary to furnish the cylinder with a grease-cup fitted with two cocks, so arranged that it may be filled with the lower one closed to prevent the escape of steam, and emptied into the cylinder by closing the upper cock and opening the lower one, so that it may gradually find its way from the cup to the cylinder. As this operation is necessarily a slow one, and there is no way with the ordinary appliances of hastening it, there is often much damage done for the want of some method of quickly supplying a sufficient amount of lubricating material.

The object of my invention is to force the oil or tallow to the interior of the cylinder by the pressure of the steam used for working the engine; and it consists in fitting the oil-cup with a steam-tight cover that may be

easily removed, and in connecting the cup with the steam-pipe of the engine above its connection with the steam chest.

To enable others skilled in the art to which it appertains to make and use my invention, I will proceed to describe its construction and operation, with reference to the drawing.

The grease-cup *a* is secured to the cylinder of the engine, and is furnished with a cock, *b*, in the usual manner. It is fitted with the steam-tight cover *c*, which is screwed on by means of the handle *d*. The small steam-pipe *e* is also fitted with a cock, and connects the grease-cup with the steam-pipe of the engine, (represented at *f*,) above the stop-valve *g*. When the cup *a* has been filled with oil or tallow, and the cover *c* screwed tightly in its place, the opening of the cock in the steam-pipe *e* causes the grease to be forced from the cup to the cylinder immediately on opening the cock *b* in the lower part of the cup. As the piston moves from the steam, it is manifest that the pressure of steam within the cylinder is not so great as that in the steam-pipe or boiler; hence the connection of the grease-cup to either of the latter, and the consequent exposure of the grease to a pressure exceeding that within the cylinder, insures its speedy transfer from the cup. No separate vessel need be used for melting tallow in connection with this grease-cup, as the rough tallow may be placed in the cup and allowed to melt there, in readiness for instant use when it may be required.

The oil-pipe may be connected with a bearing or other portion of machinery that is not easily accessible with an ordinary oil-can, in such a manner that it may be lubricated from the engine-room, if desired, or any other convenient place, by means of the pressure of the steam.

I claim as my invention and desire to secure by Letters Patent—

A grease or tallow cup fitted with a movable cover and a steam-pipe, and constructed and arranged substantially in the manner described, for the purpose specified.

HUGH CAMPBELL.
